UNITED STATES PATENT OFFICE.

CHARLES E. M. KNIGHT, OF HUNTINGTON, INDIANA.

TRACK-SANDER.

SPECIFICATION forming part of Letters Patent No. 745,065, dated November 24, 1903.

Application filed June 10, 1903. Serial No. 160,795. (No model.)

To all whom it may concern:

Be it known that I, CHARLES E. M. KNIGHT, a citizen of the United States, residing at Huntington, in the county of Huntington, State of Indiana, have invented certain new and useful Improvements in Track-Sanders; and I do hereby declare the following to be a full, clear, and exact description of the invention, such as will enable others skilled in the art to which it appertains to make and use the same.

This invention relates to sanding devices for cars; and it has for its object to provide a pneumatically-operated means for feeding the sand from the sand-box to the rail, a further object of the invention being to provide a construction which may be adjusted to secure the best results under different specific conditions and in which the feed of the sand may be graduated.

An additional object of the invention is to provide a construction from which any obstructions may be removed readily and without disjointing the several parts of the apparatus.

In the drawings forming a portion of this specification, and in which like numerals of reference indicate similar parts in both of the views, Figure 1 is a side elevation showing a sanding apparatus embodying the present invention. Fig. 2 is a vertical section through the head or casing of the sander.

Referring now to the drawings, the present sander comprises a sand-box 5, from which 35 leads what may be termed a "suction-pipe" 6, which extends downwardly and through which sand from the sand-box is drawn for discharge to the track. Engaged with the lower end of the suction-pipe is a head or 40 casing 7, having the vertical tubular branches 8 and 9, which align, and the horizontally-aligning tubular branches 10 and 11, the suction-pipe having threaded engagement in the upper branch 8 of the casing. Within the 45 branch 10 of the casing is screwed a bushing 12, and into the inner end of the bushing and lying within the casing and in axial alignment with the branches 10 and 11 of the casing is a nozzle 13, having a head 14 at its free end, which lies just short of the inner end of the branch 11 of the casing and with its face in close relation to the inner end of the bush-

ing 14', which is screwed into the branch 11 of the casing. The outer end of the bushing 14' is threaded to receive the discharge-pipe 55 or delivery-pipe 15, through which the sand from the casing is blown to the track to be sanded, said pipe extending outwardly or horizontally and then downwardly and rearwardly, so that it may lie with its discharge 60 end close to the surface of the rail to be sanded and just in advance of a car-wheel.

The inner end of the bushing 14' is gradually increased in internal diameter from the point of engagement of the discharge-pipe to 65 the inner end of the bushing, so that the sand may flow unobstructedly from the casing to the bushing.

The lower branch 9 of the casing 7 is internally threaded to receive a plug 16, which is 70 screwed thereinto and is removable, so that access may be had to the interior of the casing to permit of removal of any obstructions that may pass from the sand-box into the casing.

In the outer end of the bushing that is engaged in the branch 10 of the casing is engaged an air-supply pipe 17, from which air is forced through the nipple and into the bushing 14', so that by suction in the pipe 6 80 and the casing 7, the sand is drawn from the sand-box into the casing and then blown out through the bushing 14' into the delivery-pipe 15, through which it is forced and discharged onto the track. It will be understood, of course, that the sand will fall into the casing in great part by its own weight; but the suction established insures an even feed of sand.

By the use of the bushings described and 90 the arrangement of the air-discharge nozzle the different parts of the apparatus may be readily adjusted to obtain a greater or lesser discharge of sand, it being understood that in practice modifications of the specific construction shown may be made and that any suitable materials and proportions may be used for the various parts without departing from the spirit of the invention.

What is claimed is—

In a sanding apparatus, the combination with a casing having vertically-aligning tubular branches and horizontally-aligning tubular branches, of a sand-box having a suction-pipe

depending therefrom and engaged in the upper vertical branch of the casing, a bushing in one of the horizontal branches of the casing, and an air-supply pipe connected with the opposite horizontal branch, a nozzle within the casing connected adjustably with the air-supply pipe and having a head at its discharge end, the nozzle being adapted to move toward and away from the bushing thereby moving the said head toward and

away from the inner edge of the said bushing to vary the sand-supply, and a plug removably engaged in the lower vertical branch of the casing.

In testimony whereof I affix my signature in presence of two witnesses.

CHARLES E. M. KNIGHT.
